UNITED STATES PATENT OFFICE.

CHARLES L. THOMAS, OF AMSTERDAM, NEW YORK, ASSIGNOR TO W. S. SHULER SPRING COMPANY, OF AMSTERDAM, NEW YORK, A CORPORATION OF MAINE.

WAGON-SPRING.

SPECIFICATION forming part of Letters Patent No. 757,578, dated April 19, 1904.

Application filed October 7, 1902. Serial No. 126,281. (No model.)

To all whom it may concern:

Be it known that I, CHARLES L. THOMAS, residing at Amsterdam, in the county of Montgomery and State of New York, have invented 5 certain new and useful Improvements in Wagon-Springs, of which the following is a full, clear, and exact description, such as will enable others skilled in the art to which it appertains to make and use the same.

10 This invention relates to springs for wagons and other vehicles, more especially to springs adapted to be used with an ordinary lumber-wagon to cushion a supplemental bolster upon the hounds or axles; and to this end the invention consists in the features of construction, combinations of elements, and arrangements of parts, which will be hereinafter more fully described and the novel features thereof specifically pointed out in the claims.

20 In the accompanying drawings, Figure 1 is a view in perspective showing the bolster and side guides of an ordinary lumber-wagon with my improved supplemental bolster-springs for supporting the wagon-body, which is shown 25 in dotted lines. Fig. 2 is a bottom plan view of a supplemental bolster and spring-rigging therefor detached. Fig. 3 is a detail of a one-piece coil-spring, which is connected directly to the bolster. Fig. 4 is a detail of a 30 stirrup which rests on the bolster, and Fig. 5 is a sectional detail showing the means for securing the bolster-spring to the supplemental bolster.

Similar reference characters refer to similar parts throughout the several views.

35 The bolster (indicated at 1) and the side guides or standards 2 are of the usual and well-known construction. The wagon-body (shown in dotted lines at A) is supported from said bolster by the interposition of supplemental bolsters, which are adapted for vertical movement in order to cushion the wagon-body by means of the spring-supports, as shown. Each supplemental bolster is composed of two 40 spaced bars or beams 3, which are connected by cross-pieces 4, extending across the upper sides of the beams. The ends of each supplemental bolster are supported by springs

made of a single rod or length of steel and comprising coils 5, located beneath the supplemental-bolster beams 3 and inwardly from the end thereof. From each coil an arm 6 extends beneath the beam toward the outer end of the supplemental bolster, and at the outer end they are bent up, as at 7, and connected 55 by the cross-arm 8, which is substantially in the plane of the upper side of the supplemental bolster, as shown. From the other side of the coils 5 arms 9 extend outwardly and downwardly and are provided at the end 60 with eyes 10. These eyes are adapted to have a swinging fit on the outwardly-projecting arms 11 of stirrups 12, which are adapted to rest upon the bolster 1, and they are held thereon by nuts 13. The arch or bend of the stirrups 12 is such that the outwardly-projecting arms 11 are brought well down below the upper edge of bolster 1 in order to secure a maximum amount of spring action for the arms 9. The arms 6 of the coil-springs are secured to 70 the supplemental-bolster beams by eyebolts 14, which pass up through the supplemental-bolster beams and are secured at their upper ends, so that they may be readily adjusted or removed, by suitable nuts 15, resting in countersinks on the upper sides of the supplemental-bolster beams, as shown in section on Fig. 5. Upon inspection of Figs. 1 and 2 it will be seen that I have thus provided a construction 75 wherein the supplemental bolster is free to move downward without having its movement limited by contact with other parts until the cross-pieces 4 contact with the upper edges of the bolster 1. The distance between the two coils 5 of each spring is such that the coils may 80 pass down upon the sides of the bolster, thus preventing contact therebetween. The connecting cross-arm 8 is bent upwardly, as described, to lie substantially in the plane of the upper edge of the supplemental bolster, so that 85 it is out of the way and will not limit the movement of the supplemental bolster before such movement is checked by the cross-piece 4. Moreover, inasmuch as the ends of the arms 9 are connected to the low-lying arms 11 of 90 95 the stirrup which straddles the bolster these

arms are allowed sufficient spring movement and at the same time are out of the path of movement of the other parts.

The advantages of this construction in providing for a maximum spring action of the supplemental bolsters and in providing a light yet strong spring-rigging will be clearly apparent from the description already given. It is desirable to have a low-hanging body or body wherein the center of gravity is brought as low as possible, while at the same time providing a sufficient spring-support therefor. This is accomplished by my construction and arrangement of springs with relation to the supplemental bolster such that the supplemental bolster may be depressed to the level of the bolster without having its motion interfered with by the spring-support. A further advantage consists in the fact that the supplemental bolster, with its spring-support, is an independent element which may be readily placed in position upon an ordinary lumber-wagon before the body is placed thereon or may be readily removed, so that the wagon may be used without the supplemental bolster and spring, as will be apparent from the construction illustrated. Various other advantages will be apparent upon inspection without the necessity of particularly pointing them out, and it is to be understood that various changes in detail of construction will be readily suggested which will not depart from the scope of this invention.

Having described my invention, what I claim as new, and desire to secure by Letters Patent, is—

1. In a device of the class described, in combination with a wagon-bolster, a body-supporting supplemental bolster, having spaced

supplemental-bolster beams 3, 3 and cross-bars 4, 4 connecting the upper side of said supplemental-bolster beams, stirrups 12 adapted to straddle the wagon-bolster, and a one-piece coil-spring at each end of said supplemental bolster provided with coils 5, 5, arms 6 extending along the under side of said supplemental-bolster bars and suitably connected thereto, the connecting part 8 between said arms being bent upwardly so that it lies in substantially the plane of the upper side of said supplemental-bolster beams, and the spring-arms 9 extending downwardly from said coils and pivotally supported from said stirrups.

2. In combination, a wagon-bolster, a stirrup supported thereon, an integral spring engaging the ends of said stirrup and extending inwardly therefrom, coils in said spring, a supplemental bolster, and an extension of said spring joining said coils and projecting outwardly and upwardly to engage the bottom and end of said supplemental bolster.

3. In combination, a bolster, a stirrup supported thereon, an integral spring secured to the ends of said stirrup and extending inwardly, coils in said spring, a supplemental bolster, a connection between said coils engaging the bottom and end of said supplemental bolster, and an opening in said supplemental bolster adapted to permit the free action of the spring.

In testimony whereof I affix my signature in the presence of two witnesses.

CHARLES L. THOMAS.
